(57) **CLAIM**

The ornamental design for a bottle, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view showing a first embodiment of my new design including grayscale shades without specific colors;

FIG. 2 is a front view of the first embodiment;

FIG. 3 is a rear view of the first embodiment;

FIG. 4 is a left side view of the first embodiment;

FIG. 5 is a right side view of the first embodiment;

FIG. 6 is a top view of the first embodiment;

FIG. 7 is a bottom view of the first embodiment;

FIG. 8 is a perspective view showing a second embodiment of my design which differs front the first embodiment in having modified shade contrast;

FIG. 9 is a front view of the second embodiment;

FIG. 10 is a rear view of the second embodiment;

FIG. 11 is a left side view of the second embodiment;

FIG. 12 is a right side view of the second embodiment;

FIG. 13 is a top view of the second embodiment;

FIG. 14 is a bottom view of the second embodiment;

FIG. 15 is a perspective view showing a third embodiment of my design including the specific colors shows;

FIG. 16 is a front view of the third embodiment;

FIG. 17 is a rear view of the third embodiment;

FIG. 18 is a left side view of the third embodiment;

FIG. 19 is a right side view of the third embodiment;

FIG. 20 is a top view of the third embodiment;

FIG. 21 is a bottom view of the third embodiment;

FIG. 22 is a perspective view showing a fourth embodiment of my design including the specific colors shown; and in which differs from the third embodiment in the specific color of the head, front label border and back label;

FIG. 23 is a front view of the fourth embodiment;

FIG. 24 is a rear view of the fourth embodiment;

FIG. 25 is a left side view of the fourth embodiment;

FIG. 26 is a right side view of the fourth embodiment;

FIG. 27 is a top view of the fourth embodiment; and,

FIG. 28 is a bottom view of the fourth embodiment.
